(57) **CLAIM**

The ornamental design for a clip-style light, as shown and described.

DESCRIPTION

FIG. 1 is a perspective view of a clip-style light showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a second perspective view thereof.

The broken line immediately adjacent to the shaded area represents unclaimed boundaries of the design. The broken line showing of the remainder of the light is for environmental purposes only and forms no part of the claimed design. The un-shown bottom of the clip-style light forms no part of the claimed design.
